UNITED STATES PATENT OFFICE.

CONRAD VAUGHAN, OF CLEVELAND, OHIO, ASSIGNOR TO THE PERMOLD COMPANY, OF CLEVELAND, OHIO, A CORPORATION OF OHIO.

MOLD.

Application filed October 23, 1924. Serial No. 745,408.

This invention relates to mold cores and has for its object to provide a sectional mold core of uniform transverse dimensions which can be readily removed from a casting without damage either to the core or casting.

It is an object of the present invention to avoid the necessity in forming the outer faces of mold cores with a taper or draft to enable them to be freed from a casting whereby castings may be formed which have openings of uniform cross sectional dimensions throughout the length thereof.

A further object of the invention is to provide a sectional core formed of longitudinally tapered sections which interfit in such manner that the sections directly engaging the casting may be freed from frictional engagement with the casting before they are removed so that the core can be removed from a hot casting without danger of damaging the same.

The following description and accompanying drawings set forth in detail certain means embodying the invention, the disclosed means, however, constituting but one of the various mechanical forms in which the principle of the invention may be employed.

Referring to the accompanying drawings forming a part of this specification.

Figure 1 is a top plan view of the mold of which a core embodying the present invention forms a part.

Fig. 2 is a side elevation of the mold with the core in place.

Fig. 3 is a transverse vertical section through the center of the mold showing the core and casting in section.

Fig. 4 is a horizontal section through the mold.

Fig. 5 is a top plan view of the sectional core.

Fig. 6 is a transverse section showing the sections of the core separated.

Fig. 7 is a bottom plan view of the sectional core.

Figs. 8 and 9 are side elevations of a tapered core section employed for two opposite corner portions of the core.

Figs. 10 and 11 are side elevations of the core section employed for the other two corner portions of the core.

Figs. 12 and 13 are side elevations of the inner or key section of the core.

Figs. 14 and 15 are views showing the casting formed by the mold herein shown, Fig. 14 being an axial section and Fig. 15 being a top plan view.

Fig. 16 is a fragmentary sectional view similar to Fig. 3 showing the core applied to a casting with a shouldered inner surface.

Referring to the accompanying drawings the mold comprises two substantially identical side sections 1 mounted for movement into and out of engagement with each other upon a supporting bed 2, the two sections having complementary cavities in their meeting faces which have a shape corresponding to the contour of the outer surface of the casting which the mold is designed to produce, the sections also having complementary passages extending from the cavities to the tops of the sections to form the gate 3 through which the molten metal is introduced into the interior of the mold and the riser 3a. The bed 2 is provided along opposite sides with guide rails 4 between which the sections 1 are slidably mounted, each section being connected to a hand lever 5 by means of which it may be shifted to or from its operative position. As shown in Figs. 3, 14 and 15 the mold herein shown is designed to form a relatively thin walled, hollow casting having a tubular body 6 and flanged ends 7, the casting shown being a reel, the body of which is rectangular in cross section.

The present invention resides in the core of the mold which has an enlarged upper end portion A which is clamped between recessed portions of the side members 1 of the mold and rests thereon, and a body portion B which is of uniform transverse dimensions throughout its length and which extends through the mold cavity to form the interior of the casting, the lower end of the core being clamped between the bottom plates 8 of the mold sections which are re-

cessed to receive the lower end of the body portion B of the core and form the bottom of the mold cavity.

As best shown in Figs. 5 to 13 the core 5 consists of a number of longitudinally tapered sections, all of which extend the full length of the core, the sections when fitted together forming a solid core body, which is of uniform transverse dimensions from one 10 end toward the other so as to form the interior of the hollow casting without taper from end to end. As shown herein, the core is in the form of a rectangular prism and the sections are so formed that those which 15 directly engage the casting may be freed from the casting prior to withdrawal from the mold cavity. Two opposite corner portions of the core comprise identical sections 11 which are triangular in cross section and 20 have inclined inner faces. The remainder of the core comprises two diagonally opposing corner sections 12 and the inner or key section 13.

As shown in Figs. 5 to 13 the corner sections 11 abut the sections 12 and 13 in planes converging toward the axis of the core in the direction opposed to that in which the core sections are withdrawn from the casting, or 25 they may be said to diverge from the axis 30 of the core in the direction of withdrawal. The inner or key section 13 abuts the adjacent surfaces of the corner sections 12 in two planes which intersect the diagonal of the prism through the corners 12 and the section 35 13 similarly abuts the adjacent surfaces of the corner section 11 in two planes which intersect the diagonal through the corners 11. Thus the sections of the core abut in four divisional planes converging toward the 40 axis of the core. The divisional planes are so disposed that their lines of intersection are beyond the end of the core so that the sections extend the full length of the core. The converging pairs of divisional planes 45 may be, as shown herein, equally inclined with respect to the longitudinal axis of the core, in which case the two sections 11 and the two sections 12 of the core are interchangeable.

50 The enlarged ends of the sections 11, 12 and 13 of the core may be provided with integral projecting lugs 14, 15 and 16 to facilitate removal of the sections from a casting. Since the inner or key section 13 of the core 55 has its four faces converging from its upper enlarged end, this section can be readily removed by upward movement. When the section 13 is removed the two corner sections 12 are free to slide inwardly toward the 60 axis of the core and may be freed from the surface of the casting and then removed endwise from the mold cavity. After the corner sections 12 have been removed the corner sections 11 can of course be freely 65 moved.

It should be noted that each of the four sections of the core which engage with the casting are fully freed from the casting prior to withdrawal and that the sections cannot be removed except in the order above described. The sections 11 and 12 which form the outer portion of the core have shoulders 17 at their upper ends which engage with the top edges of the mold sections 1 to retain them in proper position within the mold 70 and the inner or key section 13 has a shoulder 18 at its upper end which engages the upper ends of the sections 11 and 12 to limit the movement of this wedge shaped key section into the core. 75

The outer sections 11 and 12 are each provided below the shoulders 17 on the faces thereof which form the outside of the core with a second shoulder 19 which lies at the top of the mold cavity, the portions of the sections above the shoulders 19 forming the enlarged head portion A of the core and the portions of the sections below the shoulders 19 forming the prismatic body portion B of the core which extends through the mold 80 cavity. This construction insures that the portion of the core which has been in contact with the casting will not rub against the mold upon withdrawal of the core section and thus neither the core section or the mold will become abraded by small particles 85 of the metal of the casting adhering to the core. 90

While the drawing indicates a plate 9 disposed along one corner portion of the mold cavity so that it forms a longitudinal split 10 in the casting, as shown in Figs. 14 and 15, it will be apparent that the core disclosed in this application may equally well be utilized for any casting having an opening therethrough entirely enclosed by the walls of the casting. Also, my core may be employed to mold openings which have portions of substantially the same transverse 95 dimensions, each portion having side walls made up of parallel elements. The side walls may be prismatic, cylindrical or irregularly shaped and made up of parallel elements. 100

105 It will also be seen that the principle embodied in my core may be employed in connection with molding a casting having an inner opening with a shoulder so that one portion of the core is of one cross sectional area and another portion of another cross 110 sectional area. This is indicated in Fig. 16 of the drawing, in which the casting 6^a has an inner surface 6^a with a shoulder and an enlarged inner surface 6^b. These may be 115 prismatic or cylindrical and have parallel side walls and yet will be easily formed by the core comprising parts 11' and 12', and having shoulders 20 thereon to form the shoulders on the casting. 120

125 Furthermore, it is to be understood that 130 the particular forms of apparatus shown and

described, and the particular procedure set forth, are presented for purposes of explanation and illustration and that various modifications of said apparatus and procedure 5 can be made without departing from my invention as defined in the appended claims.

What I claim is:

1. A sectional permanent core arranged to cooperate with a mold to define a core surface of quadrilateral cross section, said core having no inward draft to permit the core to be removed bodily from engagement with a casting after a casting operation, said core comprising two pairs of opposed outer sections and an inner or key section, each of the first pair of said outer sections defining portions of only two adjacent outer sides of the core, the second pair of outer sections co-operating with said first pair of sections to define the outer longitudinal surface of the core, said key section being arranged to be readily inserted intermediate said outer core sections and removed from the assembled core, the inner surfaces of the first pair of 25 sections being shaped to permit the second pair of sections to be moved inwardly toward the center of the core and vice versa when the key section is removed from the core, the second pair of sections being shaped so that inner surfaces thereof may cooperate with inner surfaces of said first pair of sections, the inner surfaces of said outer core sections and the longitudinal faces of said key section converging toward the bottom 30 of said core when said core is in assembled position.

2. A sectional permanent core arranged to cooperate with a mold to define a core surface of quadrilateral cross section, said core having no inward draft to permit the core to be removed bodily from engagement with a casting after a casting operation, said core comprising four outer longitudinal sections 35 and an inner or key section, two of said outer sections being of substantially triangular cross section, two sides of each said triangular section defining portions of adjacent outer sides of the core, the inner sides 40 of said triangular sections being substantially parallel when the core is in assembled position, a second pair of outer core sections, said second pair of sections being arranged to cooperate with said triangular core sections to define the outer longitudinal surface of the core, each of said second pair of sections having surfaces cooperating with said substantially parallel surfaces of said triangular sections, said key section being arranged to be readily inserted intermediate the outer core sections and removed from the assembled core.

3. A sectional permanent core arranged to 50 cooperate with a mold to define a core surface of quadrilateral cross section, said core having no inward draft to permit the core to be moved bodily from engagement with a casting after a casting operation, said core comprising two pairs of opposed outer

sections and an inner or key section, each of the first pair of said outer sections defining portions of only two adjacent outer sides of the core, the second pair of outer sections co-operating with said first pair of sections 55 to define the outer longitudinal surface of the core, said key section being arranged to be readily inserted intermediate said outer core sections and removed from the assembled core, the inner surfaces of the first pair of sections being shaped to permit the second pair of sections to be moved inwardly toward the center of the core and vice versa when the key section is removed from the core, the second pair of sections being shaped so that inner surfaces thereof may cooperate with inner surfaces of said first pair of sections, the inner surfaces of said outer core sections and the longitudinal faces of said key section converging toward the bottom 60 of said core when said core is in assembled position.

4. A sectional permanent core arranged to cooperate with a mold to define a core surface of quadrilateral cross section, said core having no inward draft to permit the core to be removed bodily from engagement with a casting after a casting operation, said core comprising four outer longitudinal sections 65 and an inner or key section, two of said outer sections being of substantially triangular cross section, two sides of each said triangular section defining portions of adjacent outer sides of the core, the inner sides of said triangular sections being substantially parallel when the core is in assembled position, a pair of outer core sections of pentagonal cross section, said pentagonal sections being arranged to cooperate with said triangular core sections to define the outer 70 longitudinal surface of the core, two inner sides of each pentagonal section being arranged to cooperate with the adjacent inner sides of the triangular sections, said key section being arranged to be readily inserted intermediate the outer core sections and removed from the assembled core.

5. A sectional permanent core arranged to cooperate with a mold to define a core surface of rectangular cross section, said core having no inward draft to permit the core to be removed bodily from engagement with a casting after a casting operation, said core comprising four outer longitudinal sections 75 and an inner or key longitudinal section, said outer sections being arranged to directly engage said mold to properly position said sections with respect to the mold, two of said outer sections being of substantially triangular cross section, two sides of each said triangular section defining portions of adjacent outer sides of the core, the inner sides of said triangular sections being substantially parallel when the core is in assembled position, a pair of outer core por- 80

4

tions of pentagonal cross section, said pentagonal sections being arranged to cooperate with said triangular core sections to define the outer longitudinal surface of the core, two inner sides of each pentagonal section being arranged to cooperate with the adjacent inner sides of the triangular sections, said key section being of substantially rectangular cross section, all the inner surfaces of said outer core sections and the longitudinal surfaces of said key section converging toward the bottom of said core when said core is in assembled position.

In testimony whereof, I hereunto affix my signature.

CONRAD VAUGHAN.
